UNITED STATES PATENT OFFICE.

FELIX E. MARTIN, OF LOS ANGELES, CALIFORNIA.

DOOR CONTROLLER.

Application filed February 5, 1927. Serial No. 166,134.

My invention relates to controllers for doors of the type used in garages, stables and the like.

The primary object of my invention is to provide a door controller for garages and the like whereby the doors thereof may be opened or closed by the simple turning of a handle which handle is so placed as to be accessible to an occupant of a vehicle, without alighting therefrom, when the vehicle is about to enter the garage or just after it has emerged therefrom.

A further object is to provide a door controller of the character described which will hold the doors open until the handle is turned to its closing position and which is equipped with means for automatically fastening the doors in their closed position.

Other objects and advantages will appear hereinafter, and, while I show herewith and will describe a preferred form of construction, I desire it to be understood that I do not confine my invention to such preferred form but that various changes and adaptations may be made therein without departing from the spirit of my invention as hereinafter claimed.

Referring to the drawings which accompany this specification and form a part thereof.

Fig. 1 is a horizontal sectional view of a garage showing, in plan, the main features of my door controller.

Fig. 2 is a vertical sectional view of the same garage showing a side view of the features of my door controller shown in Fig. 1, and of the fastening device associated therewith.

Fig. 3 is an enlarged sectional view of the three-way valve through which my door controller is operated.

Fig. 4 is an enlarged sectional view of the door controller shown in Figs. 1 and 2, taken on line 4—4 of Fig. 2.

Fig. 5 is a sectional view of the parts illustrated in Fig. 4, showing details of the fastening device of my door controller, the section being taken on line 5—5.

Though shown in the drawings as applied to a pair of garage doors hinged at the sides and meeting in the middle of the doorway, the usual type, it is evident that my door controller readily may be modified and adapted for use with other types of swinging doors or even with sliding doors. The controller is designed to be operated by a

fluid such as water, steam or air flowing from a constant supply, under pressure, through a control valve and a suitable pipe system.

The essential parts of my door controller are a comparatively long cylinder 10 suspended from the ceiling 11 of the garage on suitable brackets 12, a piston 13 fixed on one end of a piston rod 14 so as to work in said cylinder, a crosshead 15 fixed on the projecting end of said piston rod and connecting rods 16 hinged to said crosshead and to the doors 17 of the garage so as to swing the doors outwardly far enough to entirely clear the doorway. The front end of the cylinder is equipped with a bearing 18 in which the piston rod works and the rear end thereof is equipped with a pipe connection 19 into which the end of the pipe system 20, which carries the fluid, is screwed.

A three-way valve 21, with an operating handle 22 adapted to be manipulated by an occupant of a vehicle, is placed on a pergola or post at a suitable distance in front of the garage and at a suitable height to enable such occupant to open or close the doors without alighting from the vehicle. Pipe system 20 is connected to this valve, which may be turned in one direction to connect the pipe system with a drain pipe 23 or in the opposite direction to connect it with a supply pipe 24, as is clearly shown in Fig. 3, the former connection being shown in full lines and the latter being indicated by dotted lines.

Crosshead 15 is equipped with upwardly extending lugs 25 between the upper ends of which a roller 26 is pivoted, said roller being adapted to run on a guide bar 27 extending between said lugs 25, in parallel relation to said piston rod 14, and having one end fixed to the door frame as at 28 and the other fixed to one of said brackets 12, as at 29. A cord 30, attached to the middle of crosshead 15, as at 31, and extending through brackets 12 in parallel relation to the axis of cylinder 10, is run over a pulley 32, fixed to the rear wall 33 of the garage and has a weight 34 attached to its depending end. This weight and cord serve to pull back the crosshead and thus to close the doors when the valve is turned to its closing position.

The meeting edges of the two doors are formed so that one overlaps the other, as at 35, so that when the overlapping one is fastened neither of them can be opened. An

eye-bolt 36 is fixed in the door having the overlapping edge, and a J-bolt 37 is fixed on one end of a pivoted bar 38, adjacent said eye-bolt, so that when that end of the pivoted bar is raised the up-turned end 39 of the J-bolt will hook into said eye-bolt 36 and hold both doors fastened in their closed position. Said J-bolt 37 is provided with a horizontal attaching arm 37' which is bolted 10 to the upper side of the end portion of bar 38 in such a manner as to leave a slight space 37" between the end of said bar and the shank of said bolt. The lower end of pulling spring 42 is seated in this space and is 15 thereby retained in correct operative position. Pivoted bar 38 extends rearwardly, in parallel relation to guide bar 27, and terminates just above and in front of one end of crosshead 15, as is shown in Figs. 4 and 20 5, when the crosshead is in its rearmost position. A cam 40 is fixed on the under side of pivoted bar 38, adjacent its rear end, said cam being adapted to make contact with said crosshead, as it moves thereunder and 25 to cause the rear end of said pivoted bar to be lifted. The pivot 41 of pivoted bar 38 being between cam 40 and J-bolt 37 it is evident that the latter will be lowered as the former is raised. An upwardly pulling 30 spring 42, which serves as a restoring spring, is attached to the front end of pivoted bar 38 or to J-bolt 37 to yieldably hold the latter in its upper position.

The operation of my door controller is 35 extremely simple and positive. When it is desired to drive into the garage, the doors being closed as shown in the drawings, it is necessary only to reach out from one side of the vehicle and turn handle 22 through 40 an angle of 90°, as indicated in Fig. 1. Fluid under the pressure of the supply source is thus admitted to pipe system 20 and flows into the rear end of cylinder 10 forcing piston 13, piston rod 14 and cross-head 15 forwardly so that cam 40 operates 45 through pivoted bar 38 to lower J-bolt 37 and unfastens the doors and connecting rods 16 operate immediately to swing them open. So long as the valve is left in that position 50 the doors will be held open by the pressure of the fluid against piston 13. When the doors are to be closed handle 22 is turned in a reverse direction, through an angle of 90°. Pipe system 20 is thus connected with 55 drain pipe 23 which carries the fluid away

from cylinder 10 thus permitting piston 13 to move to the rear end of the cylinder, under the influence of weight 34 which was raised during the forward movement of the piston, and now operates to pull the doors 60 back to their closed position. As crosshead 15 nears the end of its rearward movement it again engages cam 40 and causes pivoted bar 38 to pull J-bolt 37 downwardly against the action of spring 42 which pulls it into 65 its fastening position, in engagement with eye-bolt 36, as soon as crosshead 15 has reached its rearmost position and the doors are completely closed.

Valve 21 may be made with a detachable 70 handle 22 which may be removed so that the valve can not be operated by an unauthorized person.

Having thus illustrated and described my 75 invention, I claim:

1. In a device of the class described, the combination with a door, a cross-head operatively connected with said door, and means for reciprocating said cross-head; of a pivotally supported, horizontally extending 80 bar, a J-bolt fixed to said bar, an eye bolt carried by said door with which said J-bolt co-operates, and a cam carried by said bar to co-operate with said cross-head for the purpose of fastening and unfastening said door at predetermined positions of said cross-head.

2. In a device of the class described, the combination with a door, a cross-head operatively connected with said door and means for reciprocating said cross-head; of a pivotally supported horizontally extending 90 bar, a J-bolt having a vertical shank provided with a horizontal attaching arm, means for attaching said arm to the upper 95 side of an end portion of said bar so that a slight space is provided between said shank and the end of said bar, an eye bolt on said door, an upwardly pulling spring having its lower end inserted between the 100 end of said bar and the shank of said J-bolt and being thereby secured to said attaching arm of said J-bolt, and operating means, carried by said bar on the other side of its pivot and engageable by said 105 cross-head, to provide for rocking said bar, against the opposition of said spring, to withdraw said J-bolt from said eye-bolt.

FELIX E. MARTIN.
